(Cl. D40—1)

Fig. 1 is a perspective view of a rotary mower housing embodying our new design, this view being taken from the front and to the left of the housing.

Fig. 2 is a top plan view thereof.

Fig. 3 is a bottom plan view thereof.

Fig. 4 is an elevational view of the front end thereof, the opposite or rear end being similar in appearance.

Fig. 5 is a side elevational view thereof, viewed from the left of the housing as shown in Fig. 2, the opposite side being similar in appearance.

We claim:

The ornamental design for a rotary mower housing, substantially as shown.
